DREDGE

John H. Milne, 1445 NE. 129th St., North Miami, Fla.

Filed Dec. 3, 1958, Ser. No. 53,642

Term of patent 14 years

(Cl. D71—1)

FIG. 1.

FIG. 2.

FIG. 3.

FIG. 4.

Fig. 1 is a perspective view of the dredge, showing my new design;

Fig. 2 is a side elevational view of the dredge, with the opposite side coinciding with the side shown.

Fig. 3 is a rear elevational view of the dredge; and

Fig. 4 is an enlarged fragmentary side elevational view of a portion of the dredge, illustrating the same in greater detail.

The dominant features of the design reside in the portions shown in full lines.

I claim:

The ornamental design for a dredge, as shown and described.
